(57) **CLAIM**

We claim the ornamental design for a utensil basket handle, as shown and described.

DESCRIPTION

FIG. 1 is a front perspective view of a utensil basket handle showing our new design;

FIG. 2 is a front elevational view of the utensil basket handle of FIG. 1, with the back elevational view being a mirror image of FIG. 2;

FIG. 3 is a top plan view of the utensil basket handle of FIG. 1; and,

FIG. 4 is a first side elevational view of the utensil basket handle of FIG. 1, with the second side elevational view being a mirror image of FIG. 4.

The bottom plan view is not shown and forms no part of the claimed design. The portion shown in broken lines is for illustrative purposes only and forms no part of the claimed design.
